UNITED STATES PATENT OFFICE.

FRANK C. DORMENT, OF CLEVELAND, OHIO, ASSIGNOR, BY DIRECT AND MESNE ASSIGNMENTS, TO THE MINERAL BATH CABINET COMPANY, A CORPORATION OF OHIO.

CABINET.

Application filed May 2, 1921. Serial No. 465,961.

To all whom it may concern:

Be it known that I, FRANK C. DORMENT, a citizen of the United States, residing at Cleveland, in the county of Cuyahoga and 5 State of Ohio, have invented a certain new and useful Improvement in Cabinets, of which the following is a full, clear, and exact description.

The present invention relates to a device 10 which may be broadly described as a cabinet within which the body of a person may be enclosed, with the exception of the head, for the purpose of applying to the person a steam bath or certain medicinal treatment 15 for the absorption of certain chemicals through the pores of the skin.

The object of the invention is to provide 20 a front closure of the cabinet of such a construction that a portion thereof may be so positioned as to form a screen behind which the patient may dress or undress when emerging from or for preparing for treatment.

Reference should be had to the accompanying 25 drawings forming a part of this specification in which Fig. 1 is an elevation of the device; Fig. 2 is a vertical sectional view; Fig. 3 is a sectional elevation showing the cover in open position.

Referring to the drawing, the cabinet consists of two side members 1 and 2 and a rear wall member 3. The front closure for the cabinet comprises a stationary lower portion 4 and a swinging door member 5 which is 30 hinged along one side which is indicated at 5. This door may be secured by any suitable latching device such as indicated at 7. There is a short top member 8 extending between the side members 1 and 2 but this top member does not extend to the forward edge 35 of the side members 1 and 2. Extending between the side members 1 and 2 and cooperating with the upper edge of the door 5 and the forward edge of the top portion 8 is a 40 slanting cover member 9.

On the inside of the members 1 and 2 and 45 extending in a slanting direction so as to support the cover 9 in inclined position are side bar members, one of which is indicated at 10 in Figures 2 and 3, it being understood that a similar bar member is on the side member 2. These supporting members 10 cooperate with the cover member 9 when the 50 same is in closed position.

At the upper end of the cover or closure

member 9 there are sidewardly extending rollers 11 which are positioned so that they may cooperate with the top edges of the side members 1 and 2. These roller members will drop into suitable notches which 60 are formed in the top edge of the members 1 and 2 when the cover member is in its final closed position. The cover member is provided with overlapping members such as indicated at 13 and 14 in Fig. 2, which extend over and close any crevice which may exist between the door 7 and the lower edge of the cover member 9 or the forward edge of the top member 8 and the upper edge of the closure member 9. In removing the 70 cover member 9 the lower edge of the cover is lifted and for this purpose convenient handles 15 are provided and when the cover is lifted a slight forward pull will cause the rollers 11 to come out of the shallow groove 12 in which they have previously 75 rested, and these rollers will roll along the top edge of the side members 1 and 2. Upon the inner surface of the cover member 9 there is a hook shaped bar, such as indicated at 16, which hook shaped bar extends transversely across the cover member 9.

When the cover 9 is pulled forward as before indicated, the hook 16 will move forward and will engage and hook over the upper edge of the door 5, occupying the position such as illustrated in Fig. 3 of the drawing. When in this position the door 5 may be opened carrying with it the cover member 9.

It will be noted that when the cover member 9 is in the position shown in Fig. 3 it, together with the door 5 forms a front wall for the cabinet, therefore a patient within the cabinet may disrobe, being protected 95 against the view of other persons in the room and may hang their clothes upon the hooks on the outside of the cabinet, which are indicated at 17. Likewise when the patient is through with a treatment the cover member 9 may be moved to its vertical position and so enable the patient to dress within the cabinet.

The upper edge of the cover member 9 is formed with a rounded depression 9^a and the forward edge of the top member 7 has a rounded depression 8^a, these cooperating to form an opening through which the neck of the patient may extend. For closing this opening so as to prevent circulation from 100 105 110

the interior of the cabinet through this opening a pneumatic collar may be provided. This collar may surround the neck of the patient and will be held by the shoulders of 5 the patient against the edges of the opening 8^a and 9^a thereby preventing circulation from the interior of the cabinet to the outside.

- Having described my invention, I claim—
- 10 1. A cabinet, having side walls, a top extending transversely between the side members but narrower than the width of the side walls, a front wall extending between the side members but of less height than the side walls, a cover member which extends diagonally between the front wall and the top, said cover having side extending members at one end thereof which overlie the top of each of the side walls, said cover member being movable to a substantially vertical position the side extending members of the cover moving in contact with the tops of the side walls.
  - 15 2. A cabinet having side walls, a top extending transversely between the side members but narrower than the width of the side walls, a front wall extending between the side members but of less height than the side walls, a cover member which extends diagonally between the front wall and the top, said cover having side extending rollers which overlie the top of each of the side walls, said cover being movable to a substantially vertical position, the said rollers traveling along the top edge of the said side walls and supporting the weight of the cover during the opening operation.
  - 20 3. A cabinet having side walls, a top extending transversely between the side members but narrower than the width of the side walls, a front wall extending between the side members but of less height than the side walls, a cover member which extends diagonally between the front wall and the top, said cover having side extending members at one end thereof which overlie the top of each of the side walls, said cover member being movable to a vertical position, the side extending members of the cover moving in contact with the top of the side wall, the cover member upon the inner part thereof having a transversely extending support which is adapted to engage with the upper edge of the front wall when the cover is in its open or substantially vertical position.
  - 25 4. A cabinet having side walls, a top extending transversely between the side members but narrower than the width of the side walls, a front wall extending between the side members but of less height than the side walls, a cover member which extends diagonally between the front wall and the top, said cover having side extending members at one end thereof which overlie the top of each of the side walls, said cover being movable to a substantially vertical position, the side extending members of the cover moving in contact with the tops of the side walls to support the weight of the cover during the opening operation, said cover being provided with a transversely extending member which is adapted to engage with the upper portion of the front wall whereby the cover will be supported on the said front wall when the cover is in vertical position and said cover may be moved with the front wall as a unit about the said hinges.

the side members but of less height than the side walls, a cover which extends diagonally between the front wall and the top, supporting members carried by the side walls with which the cover cooperates adjacent the edges to support the same, the said cover having side extending members adjacent the end thereof which overlie the top of each of the side walls, said cover being movable to a substantially vertical position, the side extending members of the cover moving in contact with the tops of the side walls and supporting the weight of the cover during the opening operation.

5. A cabinet having side walls, a top extending transversely between the side members but narrower than the width of the side walls, a front wall extending between the side members but of less height than the side walls, said front wall being hinged along one side thereof to form a door, a cover member which extends diagonally between the front wall and the top, said cover member being movable to a substantial vertical position and cooperating means carried by the cover and the front wall for supporting said cover in substantially vertical position, the front wall and cover when in vertical position being movable as a unit upon the hinges of the front wall.

6. A cabinet having side walls, a top extending transversely between the side members but narrower than the width of the side walls, a front wall extending between the side members but of less height than the side walls, hinges supporting said front wall at one side thereof whereby the front wall may operate as a door, a cover member extending diagonally between the front wall and the top, said cover having side extending members at one end thereof which overlie the top of each of the side walls, said cover being movable as a unit to a substantially vertical position, the side extending members of the cover moving in contact with the tops of the side walls to support the weight of the cover during the opening operation, said cover being provided with a transversely extending member which is adapted to engage with the upper portion of the front wall whereby the cover will be supported on the said front wall when the cover is in vertical position and said cover may be moved with the front wall as a unit about the said hinges.

In testimony whereof, I hereunto affix my signature.

FRANK C. DORMENT.
